US00D547867S

(12) **United States Design Patent** (10) Patent No.: **US D547,867 S**
 Malis et al. (45) Date of Patent: ** Jul. 31, 2007

(54) **SURGICAL INSTRUMENT HANDLE**

(75) Inventors: **Jerry L. Malis**, King of Prussia, PA (US); **Anthony John Groch**, Mantua, NJ (US); **Robert A. Acorcey**, Cherry Hill, NJ (US)

(73) Assignee: **Synergetics USA, Inc.**, King of Prussia, PA (US)

(**) Term: **14 Years**

(21) Appl. No.: **29/246,472**

(22) Filed: **Apr. 17, 2006**

(51) **LOC (8) Cl.** **24-02**

(52) **U.S. Cl.** **D24/144**

(58) **Field of Classification Search** D24/144, D24/112, 133, 147; D13/138.1; 606/39, 606/37, 34, 42, 45, 49

See application file for complete search history.

(57) **CLAIM**

The ornamental design for a surgical instrument handle, as shown and described.

DESCRIPTION

FIG. 1 is a top perspective of a surgical instrument handle in accordance with my new design;

FIG. 2 is a right side elevational view thereof;

FIG. 3 is a left side elevational view thereof;

FIG. 4 is a bottom plan view thereof;

FIG. 5 is a top plan view thereof;

FIG. 6 is a rear elevation view thereof; and,

FIG. 7 is a front elevation view thereof.

The broken lines in the figures are for illustrative purposes only and form no part of the claimed design.
